DESIGN FOR A PADLOCK

Peter Muller-Munk, Pittsburgh, Pa., assignor to Sargent & Company, New Haven, Conn., a corporation of Connecticut

Application November 17, 1943, Serial No. 111,712

Term of patent 3½ years

To all whom it may concern:

Be it known that I, Peter Muller-Munk, a citizen of the United States, residing in the city of Pittsburgh, in the county of Allegheny and State of Pennsylvania, have invented a new, original, and ornamental Design for a Padlock, of which the following is a specification, reference being had to the accompanying drawing forming part thereof, in which

Fig. 1 is a front elevational view of a padlock embodying my new design;

Fig. 2 is a top plan view thereof;
Fig. 3 is a bottom plan view of the padlock; and
Figs. 4 and 5 are end elevational views, respectively, of the padlock.

I claim:

The ornamental design for a padlock, substantially as shown.

PETER MULLER-MUNK.
